US00D508122S

(12) **United States Design Patent** (10) Patent No.: **US D508,122 S**
(45) Date of Patent: **** Aug. 2, 2005**

(54) **AIR FLOW DIRECTING FIXTURE FOR HEATING, AIR CONDITIONING AND VENTILATION DEVICES**

(75) Inventor: **Timothy M. Murphy**, Grapevine, TX (US)

(73) Assignee: **Coyote International L.L.C.**, Forth Worth, TX (US)

(**) Term: **14 Years**

(21) Appl. No.: **29/205,922**

(22) Filed: **May 20, 2004**

(51) LOC (8) Cl. **12-16**

(52) U.S. Cl. **D23/387**

(57) **CLAIM**

The ornamental design for an air flow directing fixture for heating, air conditioning and ventilation devices, as shown and described.

DESCRIPTION

FIG. 1 is an isometric top view of the air flow directing fixture, showing my new design;

FIG. 2 is an isometric bottom view thereof;

FIG. 3 is a top plan view thereof;

FIG. 4 is a left side view thereof;

FIG. 5 is a right side view thereof;

FIG. 6 is a front side view thereof, the opposite side being a mirror image thereof; and,

FIG. 7 is a bottom view thereof.
